Patented Aug. 10, 1915.

UNITED STATES PATENT OFFICE.

HERBERT T. HERR, OF PITTSBURGH, PENNSYLVANIA, ASSIGNOR TO THE WESTINGHOUSE MACHINE COMPANY, A CORPORATION OF PENNSYLVANIA.

TURBINE-BLADING.

1,149,366.

Specification of Letters Patent. Patented Aug. 10, 1915.

Application filed February 24, 1914. Serial No. 820,537.

To all whom it may concern:

Be it known that I, HERBERT T. HERR, a citizen of the United States, and a resident of Pittsburgh, in the county of Allegheny and State of Pennsylvania, have made a new and useful Invention in Turbine-Blading, of which the following is a specification.

This invention relates to blading for elastic fluid turbines and particularly to means for securing together the outer or free ends of the blades included in one row.

An object of this invention is to provide improved means for securing together the outer ends of the blades of a row and for providing an improved shroud or cover for the row of blades.

With certain types of blades it is desirable to provide a cover for the outer or free ends of the blades of a row, so that an invention closed fluid passage is provided between each two blades. In addition to this, it is essential to provide means for securing the outer ends of the blades together so that the vibration creating shocks or strains, to which the blades are subjected are resisted by several blades of a row instead of a single blade.

In the drawings accompanying and forming a part of this application: Figure 1 is a side elevation of the rotor element of a turbine shown in connection with a row of blades embodying my invention; Fig. 2 is a fragmental, longitudinal, sectional view of the rotor element shown in connection with rotating blades mounted on the element, and Fig. 3 is a perspective view of a blade, which may be employed in carrying out the illustrated embodiment of my invention.

The rotor, or blade-mounting element 4 illustrated, is provided with lateral or overhanging flanges 5 in each of which a series of blade-receiving slots 6 is cut across its lateral face. Each of the slots 6 extends radially with relation to the center of curvature of the rotor or curved blade-mounting element and is just the proper depth and width to receive the mounting shank of a blade 7.

Each of the blades illustrated is provided with a mounting shank 8 which is substantially T-shape and is adapted to be inserted laterally into one of the slots 6 so that its cross bar 9 engages the inner peripheral face 55 of the flange 5 on which the blade is mount-

ed. The body portion proper of each blade is substantially crescent shape in cross section and, as is customary, is provided with a concave rear or working face and a convex front face.

A cover or spacing piece 11 is integrally formed at the outer or free end of each blade and, as illustrated, is rectangular in shape, being so located on the blade that it extends substantially at right angles to and overhangs the concave working face. The rectangular construction employed also causes the forward edges of the cover 11 to overhang the convex face of the blade. These forward edges are reduced in thickness so that they are capable of being overlapped by the rear edge of an adjacent cover 11 when the blades are assembled, so that the covers 11 coöperate to form a continuous shroud. The rectangular covers are employed on the blades to facilitate the mounting of the blades on the particular blade-mounting element illustrated, since the shank 8 of each blade can be inserted into one of the slots 6 and each blade can be moved independently to place, it being understood, of course, that the slots 6 are so spaced that the covers 11 of the blades coöperate to form the organized shroud when the blades are assembled in a row on the element.

For the purpose of securing the separate blades together and of thereby resisting the vibration creating strains to which the blades are subjected during the operation of the turbine, I have provided a strip of metal 12 which lies against the outer peripheral face of the organized shroud and which is adapted to be secured to each cover 11 by being spot-welded or autogenously soldered thereto. The strip 12 may be circular in form, so that all of the blades of a row are secured together, or it may be formed in arc-shape sections so that groups of adjacent blades are secured together. It will, of course, be understood that my invention may be employed with any kind of a blade-mounting element and that it may also be employed with any type of turbine blades, and that, while I have described what I now consider to be a preferred form of my invention, various changes, modifications and substitutions may be made in the details of construction without departing from the spirit and scope of my invention as set forth by the appended claims.

What I claim is:

1. The combination with turbine blades or buckets provided with integral spacing pieces for the outer ends thereof, of a tie member 5 engaging the outer ends of the blades and welded thereto.
2. In combination with the blade-mounting element of a turbine, a row of blades mounted on the element, a spacing piece integrally formed with each of said blades, said blades being so located on said blade-mounting element that the spacing pieces overlap to form an organized shroud, and a tie member spot welded to said pieces.
3. In combination with the blade-mounting element of a turbine, an annular row of blades mounted on the element, a spacing piece for the outer end of each blade, integrally formed on each blade, said blades 20 being so mounted on said element that the spacing pieces overlap to form an organized continuous annular shroud for the row, and a tie member engaging the outer peripheral face of said pieces and secured thereto by the application of a welding heat.
4. In combination with the blade-mounting element of a turbine, an annular row of blades mounted on the element, a spacing

piece for the outer end of each blade, integrally formed on each blade, said blades 30 being so mounted on said element that the spacing pieces cooperate to form an organized continuous annular shroud for the row, and a sectional tie member engaging the outer peripheral faces of said pieces, each 35 section being welded to the faces engaged thereby.

5. In combination with the blade mounting element of an apparatus of the character described, blades mounted in an annular row on said element, a shroud piece for each blade, said blades being so located on said element that shroud pieces of adjacent blades overlap to form an organized shroud for a plurality of the blades of said row, and a tie 45 member positively secured to each shroud piece included in the organized shroud and extending circumferentially with relation to the shroud.

In testimony whereof, I have hereunto 50 subscribed my name this 19th day of February, 1914.

HERBERT T. HERR.
